UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

POWER SHOVEL.

Application filed January 18, 1923. Serial No. 313,360.

To all whom it may concern:

Be it known, that I, PAUL BURKE, a citizen of the United States, and resident of Green Bay, in the county of Brown and State of Wisconsin, have invented a certain new and useful Improvement in Power Shovels, of which the following is a specification.

This invention relates to power-shovels, and more particularly to that type of shovel in which the hoisting-rope or cable is also used for thrusting the dipper into the material to be excavated.

One of the objects of this invention is to improve and simplify power-shovels of the rope-thrusting type and to provide for the thrusting of a two-part or double stick dipper handle without the usual gear mechanism or rack and pinions, or auxiliary driving apparatus of any kind, and to arrange the ropes or lines for controlling and actuating the dipper so as to avoid the use of drums and to permit the ropes to be efficiently guided over the sheaves.

A further object of the invention is to provide a shovel in which the two-part hoisting line for the dipper has a bight in end-thrust engagement with the two-part dipper handle.

The invention further consists in the several features hereinafter set forth and more particularly defined by claims at the conclusion hereof.

In the drawings; Fig. 1 is a side elevation view of a power-shovel embodying the invention; Fig. 2 is a plan view thereof, partly in section; Fig. 3 is a sectional view through the guiding mechanism for the dipper handle.

In the drawings the numeral 5 designates the boom, which may be of any suitable construction, vertically pivotally attached at its lower end to a rotating base 6 of the machine, said base being of well-known construction. A hoisting-drum 7 and an auxiliary drum 8 are mounted on the base 6 in any suitable manner and driven from the prime mover (not shown) on the base. The drums 7 and 8 may be of any well-known construction equipped with clutches and brakes to control their operation. The boom is adapted to be raised or lowered in various positions of vertical adjustment by any well-known means, such as a cable 9, shown in

dotted lines, connecting pulleys 10 at the

outer ends of the boom to parts on the rotating base. The boom shown is of the box girder type with the two-part stick or dipper handle 11 working adjacent its sides 12.

The shipper shaft 13 is secured to opposite sides of the boom and the guiding means for the stick is loose on said shaft and preferably swings behind it. This guiding means consists of a saddle-block 14 for each section of the stick, said block 14 having an arm 16 carrying a shaft or stud 17 on which a guide roller 18 is loosely mounted. Each part of the stick slides between the flat surface 19 of the saddle-block immediately adjacent the shaft 13 and the roller 18, and may have a metal covering 20.

The dipper or shovel 21 carried by the stick may be of any suitable construction.

The inward-thrusting cable 22 is connected to the drum 8 and directly to the dipper and dipper handle, as at 23, and is guided intermediate its ends by sheaves 24 and 25. The sheave 24 is mounted above the boom rearwardly of the shipper shaft and the sheave 25 is loosely mounted on the shipper shaft. The cable run over the sheaves 24 and 25 is substantially alined with the drum and with the dipper stick so as to minimize wear. It will be understood that the lower plate of the boom is suitably slotted to permit the free passage of the cable 22 for the various positions assumed by the dipper handle.

Spaced sheaves 26 and 27 are mounted on a shaft 28 on the outer end portion of the boom and a padlock sheave 29 is mounted on the dipper transversely or at right angles to the axis of the sheaves 26 and 27. A sheave 30 is loosely mounted on the shipper shaft 13 between the guide for one part of the handle and the adjacent side of the boom and a collar 31 is loosely mounted on said shaft 13 between the guide for one part of the handle and the adjacent side of the boom.

The two parts of the dipper handle are connected together at their upper end portions by a member 32 and a sheave 33 is mounted thereon obliquely to the shipper shaft and so that its periphery is tangent to the sheave 30 and alines with the collar 31.

The hoisting and thrusting cable 34 extends from the drum 7 over the sheave 27, around the padlock 29, over the sheave 26, around the sheave 30 and over the sheave 33,

and is anchored to the collar 31 and hence dead-ended on the boom, through the swinging anchorage connection thus provided. This reeving of the cable produces a two-part line hoist portion for hoisting the dipper and a two-part line portion in end-thrust engagement with the dipper handle for crowding the dipper, and the cable 34 has its run over the sheave 33 maintained in the same relation thereto irrespective of the angular position of the dipper handle with respect to the boom, and the arrangement further makes it unnecessary to have a double wrap of cable.

15 With the construction above described, when the drum 8 is prevented from turning by its brake, thereby holding the line or cable 22, and the line 34 is pulled in, the dipper moves in the arc of a circle of which 20 the dipper shaft is the center. If it is desired to crowd further into the bank or to move the dipper farther out, as in loading a wagon, the braking effect on the line 22 is released slightly, whereupon the line 34, 25 working over the upper end of the dipper stick, upon being pulled in, forces or thrusts the dipper stick outward. Conversely, if it is desired to move the dipper farther in and toward the boom, releasing 30 the brake on line 34 and pulling in on line 22 by the operation of drum 8 produces this effect. Thus, by the proper manipulation and control of the lines 22 and 34 through the rotation or braking of the drums 7 and 35 8, any desired swinging or thrusting movement of the dipper and its handle may be effected. Furthermore, by the sheave arrangement above described, the thrusting action is substantially as great as the lifting 40 action on the dipper. It will also be noted that the thrusting action on the dipper is proportional to the load upon the dipper and to the resistance and weight of the material it encounters during digging.

45 It will be further noted that by swinging the dipper handle back of the shipper shaft the arrangement of the thrusting cables is facilitated and that the arrangement of the guides for said cables prevents their interference with the swinging of the dipper.

I desire it to be understood that this invention is not to be limited to any specific form or arrangement of parts except in so far as such limitations are specified in the 55 claims.

What I claim as my invention is:

1. In an excavating shovel, the combination of a boom, a dipper and a divided dipper handle mounted thereon to swing and shift with respect thereto, a connection be-

tween the parts of said handle above the boom, a dipper-hoisting-and-thrusting cable having a bight connected with the dipper for hoisting and a bight in end-thrust engagement with said connection for thrusting the dipper outwardly, and separate means for moving said dipper inwardly.

2. In an excavating shovel, the combination of a boom, a dipper and a divided dipper handle mounted thereon to swing and shift with respect thereto, a connection between the parts of said handle above the boom, a dipper-hoisting-and-thrusting cable having a bight connected with the dipper for hoisting and a bight in end-thrust engagement with said connection for thrusting the dipper outwardly, and a cable running between the parts of the handle for moving the dipper inwardly.

3. In an excavating shovel, the combination of a boom, a shipper shaft, a dipper and a divided dipper handle mounted to swing and shift with respect to the boom, a sheave on said shipper shaft, a cable anchorage on said shipper shaft, a connection between the parts of said handle above the boom and carrying a sheave having its axis disposed at an angle to that of the shipper shaft, a dipper-hoisting-and-thrusting cable having a bight connected with the dipper for hoisting and a part extending over said sheave on the shipper shaft, the sheave on the dipper handle and connected to said anchorage for thrusting the dipper outwardly, another sheave on said shipper shaft and between the parts of said handle, and a cable extending over said last-named sheave and connected to the dipper and dipper handle for moving them inwardly.

4. In an excavating shovel, the combination of a boom, a shipper shaft, a dipper and a divided dipper handle, a shipper shaft mounted on the boom, guiding means for the parts of said handle mounted on said shaft outside the boom, a sheave on said shaft between said boom and the guide means for one part of the handle, a swinging cable-anchorage on said shaft between said boom and the guide means for the other part of the handle, a sheave operatively connected to the parts of said dipper handle above the boom, a dipper-hoisting-and-thrusting cable having a bight connected for hoisting the dipper and a part extending over said sheave on the shipper shaft, the sheave on the dipper handle and connected to said anchorage for thrusting the dipper outwardly, and a cable working between the parts of the handle for moving the dipper inwardly.

PAUL BURKE.
